SHEET POLISHING MACHINE

Saul Blickman, New York, N. Y.

Application May 5, 1937, Serial No. 140,943

2 Claims. (Cl. 51—143)

This invention relates to a machine for polishing sheet material, such as metal sheets.

More particularly stated, the invention relates to the type of sheet polishing mechanism in which the sheet is reciprocated back and forth under polishing means, such for instance, as an endless sanding belt. The belt is driven at a high rate of speed during the polishing operation and one feature of the invention relates to the proper alinement and tensioning of the polishing belt.

Moreover, it has been found that sanding belts in polishing machines of the type described, do not give a uniform polish and finish to the sheet being polished.

For instance, such belts are not uniform in texture, especially after they have been used a short time. They have a tendency to stretch on one edge or the other which tends to cause the belt to run off the rolls.

Furthermore, the belt wears faster at the edges which causes the belt to groove the sheet at the edges. Also, slight defects in the belt cut grooves in the sheet.

Another difficulty encountered is caused by a tendency of the belt to curve at the edges which also causes grooves. The sanding belt is pressed into engagement with the sheet by a rubber surfaced roller which is often grooved by the edges of the belt.

In machines of the type specified, the sheet is clamped to a reciprocatable belt which is automatically reversed in its travel or, in other words, travels alternately in opposite directions beneath the polishing means. The sanding belt is led around a roller having a surface of cushioning material, and the sheet being polished is pressed upwardly against the sanding belt. If the automatic reversing mechanism fails to operate, the clamp which secures the sheet to the sheet feeding belt will engage and mutilate or damage the cushioned roller.

This invention has for one of its objects to provide a sheet polishing machine of the character described with simple and practical means, operable when the machine is in operation, for properly alining and properly tensioning the sanding belt.

Another object of the invention is to provide means for oscillating the sanding belt during the operation of the polishing machine in such a manner as to overcome the tendency of the belt to cause grooves in the sheet being polished and to give a smooth, uniform polish to the sheet.

Another object of the invention is to provide a polishing machine with safety stopping means

for automatically stopping the forward travel of the sheet feeding belt or the rearward travel thereof at a predetermined limit of movement thereof in either direction.

Further objects of the invention will appear from the following specification taken in connection with the drawings which form a part of this application, and in which

Fig. 1 is a side elevation of a machine constructed in accordance with the invention;

Fig. 2 is a diagrammatic top plan view of the machine illustrating the wiring connections and the automatic control therefor;

Fig. 3 is a top plan view of one of the belt guiding rollers having mechanism connected therewith for alining and adjusting the roller;

Fig. 4 is an elevational view partly in section of the structure shown in Fig. 3;

Fig. 5 is a vertical sectional elevation illustrating the roller which drives the sanding belt, and a pressure roller operating in conjunction therewith to press the sheet to be polished against the sanding belt; and

Fig. 6 is a diagrammatic view illustrating the valve control mechanism for the pressure roller.

The invention briefly described consists of a machine comprising an endless supporting and feeding belt having means thereon for clamping thereto a sheet to be polished, means for driving said belt, mechanism for automatically reversing the drive at predetermined limits of movement of the belt in opposite directions, and safety means for automatically stopping the driving motor and operating a brake when the belt reaches a predetermined movement in either forward or reverse direction. The machine also comprises guiding rollers for a sanding belt, one of the rollers being adjustable to tension the belt and also to properly align the belt.

Furthermore, the oscillation of the adjustable roller during the operation of the machine varies the contacting engagement of the belt and sheet being polished, prevents grooves in the sheet and gives a smooth and uniform finish or polish on the sheet.

Further details of the invention will appear from the following description.

In the particular embodiment of the machine illustrated in the drawings, there is shown a sheet supporting and feeding belt 10 which is mounted on rolls 11 and 12 supported on uprights 13 and 14. The belt travels back and forth over tables 15 and 16 which have mounted thereon rollers 17.

The roll 12 has a shaft 20 on which is mounted a gear 21 which meshes with a gear 22 on a shaft

23. The shaft 23 is driven by reducing gear mechanism R from a motor shaft 24 which in turn is driven by a motor M. A brake 25, hereinafter described, is interposed between the motor M and the reducing gear R.

5 The wiring connections for the operation of the motor M will now be described. In the form of the invention shown, the motor is a three phase motor, the three wires being shown at A, B and C. Three switches 30, 31 and 32 are mounted in the 10 three wires A, B and C, these switches being controlled by a solenoid S in the manner herein-after described. The three wires A, B and C lead from the switches 30, 31 and 32 to a reversing switch 35 having a switch arm 36 which is 15 normally maintained in neutral position by springs 37 and 38. From the reversing switch 35 the wires lead to the motor M.

The solenoid S is connected across the wires B and C and the wire connected to the wire B 20 leads to a switch 40 controlled by a switch arm 41 and from the switch 40 leads to a switch 42 controlled by a switch arm 43. From the switch 42 the solenoid circuit leads back to the wire C. The switches 40 and 42 are normally closed and 25 the solenoid S is normally energized, thus maintaining the switches 30, 31 and 32 closed.

The reversing switch arm 36 is connected to a slide bar 45 suitably mounted for reciprocation and having mounted thereon a pair of limit stops 30 46 and 47.

The belt 10 has mounted thereon a plate 48 having a clamp 49 secured thereto for clamping the metal sheet 50 to the belt. The sheet 35 50 when clamped to the belt is reciprocated alternately in opposite directions.

The plate 48 has secured thereto and extending beyond the ends thereof and laterally of the belt 10, a pair of lugs 51 and 52 which travel 40 with the belt. The lug 52 is adapted to engage the stop members 46 and 47 at predetermined points in the forward and reverse travel of the belt. When the lug 52 engages the stop member 46 the bar 45 and the reversing switch control arm 36 are moved forwardly and the reversing switch operates in the usual well known manner to reverse the direction of drive of the motor M. It will be understood that suitable relays are 45 operated by the reversing switch to effect this motor reversing operation. As soon as the belt 50 starts its reverse travel the lug 52 will leave the stop member 46 and the bar 45 will be returned to its neutral or intermediate position by the spring 38. When the belt reaches its predetermined limit of reverse travel the lug 52 will engage the stop member 47 and operate the reversing switch to again reverse the motor and drive the belt in the forward direction.

In order to prevent an over-travel of the belt 60 in either direction in the event that the reversing mechanism fails to operate, the lug 51 is mounted to engage the switch arms 41 or 43 of the switches 40 or 42. When the lug 51 engages either one of these switch arms the circuit of the solenoid S will be opened, thus causing the switches 30, 31 and 32 to open and breaking the motor circuit.

70 The brake 25 is provided for braking the drive of the motor shaft when the motor circuit is opened. This brake is constructed in the usual well known manner and is connected by wires D and E to the wires A and B. This brake circuit is normally closed, thus holding the brake in inoperative position. However, when the brake circuit is opened upon opening of one of the switches 75

40 or 42, a spring will cause the brake to be applied to the motor shaft 24, thus stopping the rotation thereof.

The polishing mechanism utilized in the machine illustrated in the drawings consists of an 5 endless sanding belt 55 which is mounted on three rollers 56, 57 and 58. The roller 57 is the driving roller and has a surface of cushioning material. Roller 56, however, may be used as the driving roller. In order to press the sheet being polished against the sanding belt a pressure roller 60 is mounted below the cushion roller 57 and below the belt 10. The pressure roller is mounted in journal boxes 61 and 62 which are vertically slidable in brackets 63 and 64. Each journal box has extending downwardly therefrom a plunger or rod 65 which is secured at its lower end to a diaphragm 66 mounted in a dash pot 67. The dash pot has connected thereto a pair of pipes 68 and 69, the pipe 68 leading into the 10 upper part of the dash pot above the diaphragm 66, and the pipe 69 leading into the lower part of the dash pot below the diaphragm 66. The diaphragm 66 is flexibly mounted and is adapted to move upwardly or downwardly, depending on 15 the pressure applied to the dash pot.

The pressure in the dash pot is controlled by a valve 70, shown diagrammatically in Fig. 6. The valve casing has a pressure inlet pipe 71 and exhaust outlet pipes 72 and 73. When the valve 30 70 is adjusted to the position shown in the upper portion of Fig. 6 the pressure pipe 71 is connected to the pipe 69 and pressure is applied to the lower end of the dash pot, thus forcing the plunger 65 upwardly and pressing the pressure roller 60 in an upward direction to press the sheet being polished against the sanding belt 55. In this position of adjustment of the valve 35 70 the upper pipe 68 is connected to the exhaust 40 72.

In the lower portion of Fig. 6 the valve is shown in its other position of adjustment in which the pressure pipe 71 is connected to the pipe 68 and the pipe 69 is connected to the exhaust pipe 73. In this position of adjustment of the valve 45 70 the pressure roller 60 will be forced downwardly.

The valve 70 is manually controlled and pressure is applied to and released from the roller 60 as desired.

In order to properly align and tension the sanding belt 55 the roller 58 is mounted for adjustment about a vertical axis, preferably passing through the center of the roller, and is also mounted for adjustment toward and away from the roller 56 to properly tension the belt.

The roller 58 is mounted in bearings 75 and 76 carried by brackets 77 and 78 which in turn are mounted on a base frame or plate 79. The frame or plate 79 has secured to the central portion thereof and extending therebelow a circular block 80 which is rotatably mounted in a frame 81. The frame 81 has extending upwardly from the ends thereof flanges 82 and 83 which are provided with arcuate surfaces 84 which coact with arcuate end surfaces on the plate 79. The arcuate surfaces are formed on radii having for their center the center of the circular block 80.

In order to adjust the roller 58 about the axis of the block 80, an arcuate rack 85 is secured to one end of the base frame 79 and is engaged by a 70 worm 86 mounted on a shaft 87 having also secured thereto a bevel gear 88. The gear 88 is rotatable by a bevel gear 89 which meshes therewith and is mounted on a shaft 90 manually rotatable by a handle 91.

As the handle 91 is rotated in one direction or the other, the roller 58 will be swung about a vertical axis, passing through the vertical center of the roller and will thus be properly centered.

- 5 The frame 81 and the plate or base frame 79 carried thereby are supported on a fixed base 95 and are adjustable on the base to properly tension the belt 55. This adjustment is accomplished by means of a pair of screws 96 and 97 which extend 10 through and are threaded in the end portions of the frame 81. Each of these screws has mounted on the end thereof a worm 98 which engages a worm gear 99 mounted on a shaft 100 having a handle 101 secured to one end thereof.
- 15 As the shaft 100 is rotated the screws 96 and 97 will be rotated, thus moving the frames 79 and 81 and the roller 58 in one direction or the other to tighten or loosen the belt, depending on the direction of rotation of the handle 101 carried by the 20 shaft 100.

The fixed base 95 is mounted on pedestals or stanchions 102.

The roller 57, the pressure roller 60, commonly called a billy roll, the dash pots and operating 25 connections therefor are all mounted on stanchions or pedestals 103. The roller 56 is supported on stanchions 104.

Operation

30 The machine operates as follows: The sanding belt 55 is continuously driven during the operation of the machine and the manually controlled valve 70 controls the pressure of the sheet being polished against the sanding belt. The belt 10 35 which supports and feeds the sheet being polished travels alternately in opposite directions, the direction of travel being automatically reversed at predetermined limits of the forward and reverse travel by the engagement of the lug 52 with 40 the stop members 46 and 47 which operate the reversing switch and automatically reverse the motor.

However, should the reversing mechanism fail to operate, the lug 51 will engage one of the switch 45 arms 41 or 43, thus opening the circuit of the solenoid S and thereby opening the switches 30, 31 and 32 which lead to the motor. At the same time the circuit for the brake 25 will open and the 50 brake spring will operate to apply the brake to the motor shaft 24 and instantaneously stop the rotation thereof.

The belt 55 operates at a high rate of speed and the belt can be properly aligned by the operation of the handle 91 which adjusts the roller 58 about 55 a vertical axis passing through the vertical center

thereof. Furthermore, the proper tension on the belt 55 can be applied by manipulating the handle 101 which adjusts the roller 58 toward or away from the roller 56.

From the foregoing description it will be clear 5 that a simple, practical and efficient polishing machine has been designed and that the machine can be so adjusted as to properly align and tension the sanding belt and, furthermore, the supplemental safety stop mechanism will effectively 10 prevent an over-travel in either direction of the belt in the event of the failure of the reversing mechanism to operate. Thus, damage to or 15 mutilation of the cushion roll 57 is effectively prevented.

Although one specific embodiment of the invention has been particularly shown and described, it will be understood that the invention is capable of modification and that changes in the construction and in the arrangement of the various co-operating parts may be made without departing from the spirit or scope of the invention, as expressed in the following claims.

What I claim is:

1. A sheet polishing machine comprising an 25 endless sheet supporting and feeding belt, means for clamping a sheet to be polished to said belt, means including an electric motor for driving said belt, means for reversing the motor and reversing the travel of the sheet supporting belt at predetermined limits of forward and reverse travel thereof, polishing means engageable with the sheet during the travel thereof, and means including switches and control members carried by the belt for automatically stopping the motor 30 when the belt reaches predetermined limits in the travel thereof.

2. A sheet polishing machine comprising an 35 endless sheet supporting and feeding belt, means for clamping a sheet to be polished to said belt, 40 means including an electric motor for driving said belt, means for reversing the motor and reversing the travel of the sheet supporting belt at predetermined limits of forward and reverse travel thereof, polishing means engageable with the 45 sheet during the travel thereof, means including switches and control members carried by the belt for automatically stopping the motor when the belt reaches predetermined limits in the travel thereof, and brake means controlled by said 50 switches whereby the brake is operated when the switches are actuated by the switch control members.

SAUL BLICKMAN.
